UNITED STATES PATENT OFFICE

2,130,437

EXHIBITING AND ADVERTISING DEVICE

Harry W. Taylor, Oak Park, Ill.

Application June 5, 1937, Serial No. 146,549

9 Claims. (Cl. 40—130)

This invention relates to exhibiting and advertising devices and one of the objects of the invention is to provide an improved apparatus of this character which will not only attract the attention of the public, but will stimulate interest not only in the articles being exhibited or displayed thereby, but also in the device itself, the operation of which latter is of such a nature as to produce a mystifying effect.

10 A further object is to provide an improved device of this character which will be of a simple, durable, compact and inexpensive construction, and effective and efficient in operation.

To the attainment of these ends and the accomplishment of other new and useful objects as will appear, the invention consists in the features of novelty in substantially the construction, combination and arrangement of the several parts, hereinafter more fully described and 20 claimed and shown in the accompanying drawing illustrating this invention, and in which—

Figure 1 is a front elevation of a device of this character constructed in accordance with the principles of this invention.

25 Figure 2 is a vertical sectional view taken on line 2—2, Figure 3.

Figure 3 is a vertical sectional view taken on line 3—3, Figure 2.

Figure 4 is a wiring diagram.

30 Referring more particularly to the drawing, the numeral 10 designates generally a casing which may be of any desired size and configuration and constructed of any suitable material. The casing is provided with a view opening 11 in one of the walls and the cover 12 may, if desired, be removable and secured in position in any suitable manner.

Within the casing is arranged a partition 13 extending from the top to the bottom thereof, 40 dividing the casing into two compartments 14—15.

Within the compartment 15 is arranged a light-proof chamber 16 constructed in any suitable manner and of any desired or suitable size.

45 The chamber is closed and there is provided in one of the walls thereof, preferably the top, a series of openings 17, and if desired the chamber may be lined with any suitable heat insulating material, 18.

50 This chamber 16 is preferably of a size less than the interior of the casing 10 and if desired a horizontal platform or partition 19 may be provided in the casing extending to the partition 13, and is spaced for any desired distance 55 above the bottom of the casing, the platform or

partition 19 being held in position in any suitable manner.

The chamber 16 may project for any desired distance above the platform 19, and supported by the top of the chamber is a cushion 20 which 5 is provided with openings 21 therethrough which register with the respective openings 17 in the top of the chamber 16.

Upon the cushion 20 the articles 22 that are to be displayed, are placed. The cushion is constructed of any suitable soft material such as felt or the like, which cooperates with the article to form a light tight joint therebetween.

Arranged within the chamber 16 are suitable illuminating devices here shown as lamps 23 15 which are supported in any suitable manner.

In the compartment 15, and disposed in advance of the partition 13 is transparent member 24, preferably a panel of glass, which is held in position above the top of the chamber 16 and 20 preferably in proximity to the top of the casing 12, and in an inclined position. The transparent member 24 being removably supported in any suitable manner, preferably by means of the ends thereof extending into guides 25, may be readily 25 moved, if desired, when the top 12 of the casing is removed.

The walls of the compartment 15, which include the front face of the partition 13 as well as the top surface of the partition or platform 30 19, are darkened preferably by means of a coating of suitable material such as paint or the like, preferably black, as at 26.

The partition 13 may be formed in any suitable manner either entirely or partially of a removable element, the element being provided with suitable openings 27 therethrough, and which openings may be of any desired delineation so as to form words or other illustrative matter.

40 This partition 13 forms the front wall of the compartment 14 in which latter is arranged suitable illuminating means such as a lamp 28, the rays of which latter are directed through the openings 27 in the partition 13.

45 In order to accentuate the rays from this lamp 28 a portion of the wall 29 which forms a part of the casing and the back wall of the compartment 14, may be coated or covered with any suitable light coloring matter, such as white, so that 50 when the light 28 is lit the light surface 30 directing the rays through the openings 27 will cause the latter to be clearly legible.

The front surface of the partition 13 is coated with a dark coating and being disposed behind 55

the transparent member 24 becomes a reflecting surface when the light 28 is extinguished and the lights 23 are lighted. The partition 13, or the portion thereof containing the openings 27 being removable, it will be manifest that the same may be removed or interchanged with any other similar element.

The lights 23 and 28 are connected to a suitable source of supply of current and a suitable 10 flasher system is employed in the connection, whereby when one of the lights is lighted the other will be extinguished, and the flasher system operates in such a manner that the lights will be alternately lighted and extinguished first 15 to cause, for instance, the light 23 to be lighted and the light 28 to be extinguished. Under these conditions the rays from the light 23 will be directed through the articles 22 supported upon the cushions 20, while the light 28 will be extinguished.

Inasmuch as the interior of the compartment 15 and the front of the partition 13 are coated or covered with dark material, and as a portion of the partition 13 is behind the transparent member 24, the rays of light directed through the articles 22 will cause the articles 22 to be reflected by the reflector 24.

When the flasher system causes the light 23 to be extinguished and the light 28 to be lighted, 30 the articles, in the present instance being shown as eggs, will become normally opaque, and as the lights 23 are mounted within the light-proof chamber 16, no reflection will be caused from the articles but the light 28 will be lighted to 35 cause the reading matter created by the openings 27 in the partition 13 to become clearly visible.

In other words, during the operation of the device the lights 23 and 28 are alternately lighted and extinguished. When the lights 23 are lighted and the light 28 extinguished rays of light 40 will not only cause the articles 22 to become translucent but they will cause reflections of these articles to be made by the reflector 24.

Immediately upon extinguishing the light 23 45 and lighting the light 28, the reflections will become obliterated while the sign or reading matter caused by the openings 27 will become clearly visible.

Any number of lamps or lights 23 may be employed in the chamber 16, in the present exemplification of the invention two are shown, and these lamps are connected in series.

Current is supplied to the lamps from any suitable source through the medium of a plug-in 50 element 31 and a thermostatic flasher may be employed which may be located in the plug 31.

This flasher unit embodies a thermostatically controlled member 32 which is connected through the plug 31 to one side of the supply line, and 55 co-operates with a terminal 34—35, the thermostatic element being controlled by the changes of temperature created by the current.

The element 32 is connected to one side of the socket 36 of the lamp 28 by means of a conductor 60 33, and leading from the terminal 40 of the other side of this socket 36 is a conductor 39 which is also connected with the terminal 35 of the plug 31. Leading from the socket terminal 40 to one side of the socket 38a of one of the lamps 23 and 65 leading from the other side of the socket 38a of the lamp 23, is a conductor 42a which is connected to a conductor 43 leading through the plug 31 to the other side of the supply line.

70 75 Leading also from the terminal 40 is a con-

ductor 41 which is connected to one side of the socket 38 of the other lamp 23 and leading from the other side of the socket 38 is a conductor 42 which is connected with the conductor 43.

When the thermostat element 32 is in contact 5 with the terminal 35 of conductor 39, the circuit through the sockets 38a and 38 will be completed and the current will flow as follows to light the lamps 23, viz., from the side A of the supply line through contact 35, conductor 35a to terminal 10 43, where it will be divided, a portion thereof flowing through conductor 42, through the socket 38, conductor 41 to terminal 40.

The current will also flow from the terminal 43 through conductor 42a, socket 38a, conductor 41a, to terminal 40. From the terminal 40 the current flows through the socket 36, conductor 33, through the flasher and thermostat element 32 to the other side B of the supply line. This will cause the lights 23 in the sockets 38a and 38 20 to be lighted, and as the current is thus flowing, the line or conductor 39 will be dead.

When the heat in the plug 31 is sufficient to cause the flasher or thermostat element to move out of contact with the terminal of the conductor 25 33 and into contact with the terminal 39a of the conductor 39, the line or conductor 33 will be dead and the lamp in the socket 36 will be extinguished. Under these conditions the current will flow as follows to light the lights in the 30 sockets 38a—38, viz., from the line A, through the plug to terminal 35 through conductor 35a to terminal 43, dividing so that part will flow through conductor 42, through socket 38, out through conductor 41 to terminal 40. At the 35 same time the other part of the current will flow from terminal 43, through conductor 42a, socket 38a, conductor 41a, to terminal 40. From terminal 40 the current will flow through conductor 39 back to the plug terminal 35, through 40 flasher or thermostat element 32 to the other side B of the supply line. When this circuit is completed, the line or conductor 33 will be dead.

Thus it will be seen that the circuits through socket 36, and through the sockets 38a and 38, 45 will be alternately opened and closed, and will be controlled by the flasher or thermostat element 32, the latter being itself controlled or influenced by changes in temperature, or the heating or cooling of the said element.

With this arrangement the lighting and extinguishing of the lamps will be automatically controlled and they will be alternately lighted and extinguished.

While one form or wiring of a flasher system 55 has been herein shown and described it is to be understood that any other forms or wiring may be employed, to effect the alternate lighting and extinguishing of the lamps.

If desired a portion of the cover 12 may be 60 hinged as at 12a so that an operator may raise said section and directly inspect the articles 22, affording an opportunity to the operator of candling the eggs 22, if eggs are employed in the apparatus.

While the preferred form of the invention has been herein shown and described, it is to be understood that various changes may be made in the details of construction, and in the combination and arrangement of the several parts, within 70 the scope of the claims, without departing from the spirit of this invention.

What is claimed as new is:

1. An exhibiting device embodying a casing having a view opening in one wall thereof, a 75

closed light-proof chamber in the casing having an opening in one wall adapted to be closed by the article to be exhibited, illuminating means within said chamber disposed to direct its rays through the article, means for causing a reflection of the article within the casing when said illuminating means is rendered active, a sign within the casing, illuminating means for the sign, and thermostatic means common to said illuminating means for alternately rendering one active and the other inactive.

2. An exhibiting device embodying a casing having a view opening in one wall thereof, a closed light-proof chamber in the casing having an opening in one wall adapted to be closed by the article to be exhibited, illuminating means within said chamber disposed to direct its rays through the article, means for causing a reflection of the article within the casing when said illuminating means is rendered active, a sign within the casing, illuminating means for the sign, and means common to the said illuminating means and operating automatically to alternately render one active and the other inactive, said sign illuminating means being disposed behind the sign and directing its rays through predetermined portions of the sign.

3. An exhibiting device embodying a casing having a view opening in one wall thereof, a closed light-proof chamber in the casing having an opening in one wall adapted to be closed by the article to be exhibited, illuminating means within said chamber disposed to direct its rays through the article, means for causing a reflection of the article within the casing when said illuminating means is rendered active, and means operating automatically to render said illuminating means active and inactive, the said reflecting means embodying a transparent member and a darkened surface therebehind.

4. An exhibiting device embodying a casing having a view opening in one wall, the inner surfaces of the walls being darkened, a light-proof chamber in the casing, said casing having an opening in one wall adapted to be closed by the article being exhibited, an electric light in said chamber disposed to direct its rays through the article, reflecting means in the casing and beyond said chamber for causing a reflection of the article only when said light is lighted, and means operating automatically to cause said light to be alternately lighted and extinguished.

5. An exhibiting device embodying a casing having a view opening in one wall, the inner surfaces of the walls being darkened, a light-proof chamber in the casing, said casing having an opening in one wall adapted to be closed by the article being exhibited, an electric light in said chamber disposed to direct its rays through the article, reflecting means in the casing and beyond said chamber for causing a reflection of the article only when said light is lighted, and thermostatic means for causing said light to be alternately lighted and extinguished.

6. An exhibiting device embodying a casing having a view opening in one wall, the inner surfaces of the walls being darkened, a light-proof chamber in the casing, said casing having an opening in one wall adapted to be closed by the article being exhibited, an electric light in said chamber disposed to direct its rays through the article, reflecting means in the casing and beyond said chamber for causing a reflection of the article only when said light is lighted, a sign in the casing, a light in the casing for illuminating said sign, and means common to said lights and operating automatically to cause the lights to be alternately lighted and extinguished.

7. An exhibiting device embodying a casing having a view opening in one wall, the inner surfaces of the walls being darkened, a light-proof chamber in the casing, said casing having an opening in one wall adapted to be closed by the article being exhibited, an electric light in said chamber disposed to direct its rays through the article, reflecting means in the casing and beyond said chamber for causing a reflection of the article only when said light is lighted, a sign in the casing, a light in the casing for illuminating said sign, means common to said lights and operating automatically to cause the lights to be alternately lighted and extinguished, the second said light being disposed behind the sign and directing its rays through predetermined portions of the sign, and means for accentuating the rays from the last said light.

8. An exhibiting device embodying a casing having a view opening in one wall, the inner surfaces of the walls being darkened, a light-proof chamber in the casing, said casing having an opening in one wall adapted to be closed by the article being exhibited, an electric light in said chamber disposed to direct its rays through the article, reflecting means in the casing and beyond said chamber for causing a reflection of the article only when said light is lighted, a sign in the casing, a light in the casing for illuminating said sign, and means common to said lights and operating automatically to cause the lights to be alternately lighted and extinguished, said lights being isolated from each other.

9. An exhibiting device embodying a casing having a view opening in one wall, the inner surfaces of the walls being darkened, a light-proof chamber in the casing, said casing having an opening in one wall adapted to be closed by the article being exhibited, an electric light in said chamber disposed to direct its rays through the article, reflecting means in the casing and beyond said chamber for causing a reflection of the article only when said light is lighted, a sign in the casing, a light in the casing for illuminating said sign, means common to said lights and operating automatically to cause the lights to be alternately lighted and extinguished, and means common to the lights whereby they may be connected to a source of supply of current.

HARRY W. TAYLOR.
